UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,397, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The design, which is fully and clearly represented by the figure in the drawing, consists of two wide parallel stripes, A and B, which are alternated throughout the shawl. The stripe A is composed of a number of plain parallel ribs or bars, *a b c d*, &c., of varying widths and of different shades or colors; and the stripe B, which is made up of wider bars than those composing the stripe A, has be-

tween its edging *h* and center *i* a series of parallel bars, *j*, blended into each other by shading, all as shown.

Irrespective of the colors employed, I claim—

1. The design for the stripe B, as represented.
2. The design for the whole pattern, including the stripes A and B.

In testimony whereof I have signed my name to this specification in the presence of two subscribing witnesses.

FRED. WINK.
